LIGHTING FIXTURE

Howard A. Daum, R.F.D. 5, Hanover, Pa. 17331

Filed Nov. 23, 1966, Ser. No. 4,799

Term of patent 14 years

(Cl. D48—31)

FIG. 1

FIG. 2

FIG. 1 is a front elevation of a lighting fixture, showing my new design; and

FIG. 2 is a sectional view taken along the lines 2—2 in FIG. 1.

The rear elevation and side elevations of the lighting fixture are the same in appearance as the front elevation shown in FIG. 1.

I claim:

The ornamental design for a lighting fixture, substantially as shown and described.
